CLAIM

The ornamental design for a bird feeder, as shown and described.

DESCRIPTION

FIG. 1 is a perspective view taken from the top, front and left of a bird feeder showing my new design; FIG. 2 is a top plan view thereof; FIG. 3 is a front elevational view thereof; FIG. 4 is a right side elevational view thereof, the left side being a mirror image of the right side shown; and FIG. 5 is a rear elevational view thereof.
